UNITED STATES PATENT OFFICE.

JOHN H. FELLOWS, OF ENID, OKLAHOMA.

GOLD-WASHING APPARATUS.

1,316,835.

Specification of Letters Patent. Patented Sept. 23, 1919.

Application filed December 10, 1917. Serial No. 206,480.

To all whom it may concern:

Be it known that I, JOHN H. FELLOWS, a citizen of the United States, residing at Enid, in the county of Garfield and State of Oklahoma, have invented certain new and useful Improvements in Gold-Washing Apparatus, of which the following is a specification.

This invention relates in general to gold washing apparatus, and particularly to an improvement in my former Letters Patent No. 637,861 granted November 28, 1899. In said former patent I have shown and described a gold washing apparatus which, in general, comprised a main casing having a bottom, sides and an end, the bottom being turned upwardly at one end to form an upright transverse partition, a longitudinal perforated partition detachably mounted in the casing and extending at one end beyond the upright partition with gold retaining devices connected with the partition and a bottom of the main casing which comprised riffles and receptacles having deflectors, a supplemental casing connected with and adapted to receive auriferous water from the bottom of the casing and a supplemental casing connected with the longitudinal partition at a point thereof in the portion which extends beyond the upright partition and adapted to receive auriferous water therefrom.

I now propose to improve on the above construction shown and described by providing a more efficient, practical manner of collecting the gold.

In the accompanying drawing, I have shown the improvements as applied to that class of apparatus illustrated in my former patent.

In said drawing:

Figure 1 is a plan view of the main casing of the apparatus;

Fig. 2 is a longitudinal vertical section showing the supplemental casings;

Fig. 3 is a side elevation of a portion of the main casing, and

Figs. 4, 5 and 6 are vertical sections on the lines 4—4; 5—5; and 6—6 respectively of Fig. 2.

Referring to the drawings in detail, 1 represents the oblong main casing similar to the one illustrated in my former patent having an end piece 2 and side pieces 3. The end 55 opposite the end piece is open and in which is secured a transverse brace 4, and extend-

ing longitudinally of the inner surface of each of the sides 3 is a cleat 5, which divides the casing into upper and lower portions, the lower portion being closed at both ends, as shown at 2 and 6.

A riffle frame 7 is provided with side bars and transverse riffles 8 are mounted in the casing bottom and extends from the end piece 2 approximately to the end of the bottom portion of the main casing, which terminates in the upwardly directed transverse partition 6. This is all fully shown and described in my former patent, but, instead of the shallow downwardly curved receptacles, illustrated in that patent, I now propose to provide a more effective means for carrying out the purpose of these receptacles. With this end in view, the improvement in the present instance preferably comprises a receptacle 9 having staggeredly arranged sides providing a restricted bottom portion 10 and a comparatively wide upper portion 11. This bottom 10 is filled with quicksilver. Located in the upper portion 11 is a longitudinal baffle 12 which overlies the restrictive bottom portion 10 and prevents short circuiting of the water which contains the gold passing through the receptacle, that is to say, it prevents the fluid from forming an eddy in the receptacle in passing out the same end of the receptacle that it enters.

13 represents a deflector which is positioned in the path of the riffle and directs the fluid into the receptacle. As many of these receptacles may be employed in the length of the riffle as is desired; however, I have shown an example of two.

Mounted on the cleats 5 is a longitudinal partition 14 which is provided upon its face with transverse riffle bars 15. Secured to the lower surface of this partition are the heretofore mentioned deflectors 13.

The partition 14 is cut away at points and provided with screens 16 through which the finer particles of gold and other substances pass. Disposed in the casing between the receptacles 9 is a shaft 17 connected to which is a regulator blade 18 which may be turned vertically by a crank 19, see Fig. 3, connected with the shaft 17, and may be held in adjusted position by a lock plate 20 secured to one of the casing sides. The bottom of the casing, as well as the partition 14 is provided with an opening 21 in which is secured a tube 22 through which passes a shaft

23, provided with a regulator blade 24, which may be operated by means of a suitable crank.

Connected to each of the tubes 22 is a supplemental casing 25. Connected with and surrounding this central tubular portion is a casing member 26, provided with a closed top 27 which slants from the central portion to the perimeter thereof, the bottom of which is open. Surrounding this casing member 26 is a casing 28 open at the top, the bottom of which extends beneath the lower edges of the member 26. The members 28 and 26 are preferably detachably connected. Connected with and projecting through the bottom of the member 28 is a tubular casing member 29 having a closed bottom providing a quicksilver receptacle and open at the top and extending upwardly between the tubular members 25 and 26 and terminating below the top 27 of the member 26. Longitudinal baffle or retarding devices 30 are provided in the bottom of the tubular member 29. All of the above described construction is substantially the same as illustrated in my former patent, with the exception of the construction of the bottom portion of the tubular member 29. In the present instance, the bottom portion of this tubular member 29 is adapted to contain quick silver and the longitudinal baffles are employed in place of the retarding devices shown in my former patent.

The operation of the apparatus is as follows: I place quicksilver in the restricted bottom portion 10 of the receptacles 9, and in the tubular members 29, and a goldbearing stream or other water containing dirt, sand and gold particles from which the finely divided gold is to be separated, is directed upon the partition 14 at the end thereof, adjacent the end piece 2, which is preferably raised so that the partition 14 and casing bottom shall be inclined and the water flow toward the opposite ends thereof. The water falls partially upon the screen 16 and partially upon the partition 14, and part thereof passes through screen 16 and down upon the casing bottom and along the latter, flowing across riffles 15 to the receptacles 9 and into and through the tube 22 connected with the lower partition, and into the supplemental casing 25, through which it passes in a course indicated by the

arrows, and finally discharges above the casing member. That part of the water which strikes the partition 14 flows along it over the riffles 15 to the screen 16, which is located midway the length of this partition, through which a portion of it passes and joins the water which flows along the lower partition, and that portion of the water which flows along the partition 14 and crosses the last-named screen passes on to the screen in the opening 21 of the tube 22 and through it into the supplemental casing communicating therewith, and passes therethrough as indicated by the arrows, finally discharging above the top of the casing. The regulator blades 18 may be adjusted to regulate the flow and volume of water passing along the casing bottom, and the regulator blades 24 may be adjusted to regulate the flow and volume of water passing through the tubes 22 into the supplemental casings connected therewith. The screen 16, as well as the screen overlying the opening 21 in the tube 22, will separate the larger particles of gold and these will be collected by the riffles 15, the dirt and other substances passing on with the water. The riffles in the lower partition will catch and hold the larger particles of gold which pass through the screens above mentioned, and the quicksilver in the bottom portion 10 of the receptacle 9 will attract and retain the finer particles of the gold. The water entering the supplemental casings connected with the tubes 22 will contain only the finest particles of gold, and these in the tortuous course of the water will collect in the quicksilver which lies in the bottom of these casings.

I claim:

In a gold washing apparatus, a receptacle having upper and lower sections, said upper section being of greater area than said lower section, a baffle in the upper section overlying the lower section, a box-shaped deflector overlying the upper section adapted to direct the water containing gold to said upper section, said baffle adapted to cause said water to traverse said lower section and pass out of the receptacle at an opposite end from which it enters.

The foregoing specification signed at Besie, Okla., this 24th day of Sep., 1917.

JOHN H. FELLOWS.
